CLAIM

The ornamental design for a container for active substances for a diffusion evaporator, as shown.

DESCRIPTION

FIG. 1 is a front, left side perspective view of the container for active substances for a diffusion evaporator of the present invention;

FIG. 2 is a front view thereof;

FIG. 3 is a left side view thereof;

FIG. 4 is a bottom view thereof;

FIG. 5 is a right side view thereof;

FIG. 6 is a top view thereof; and,

FIG. 7 is a rear view thereof.
